ELECTRIC ADVERTISING DEVICE

Laszlo Jónap, New York, N. Y., assignor to Neolux,
Inc., New York, N. Y.

Application August 24, 1939, Serial No. 291,679

6 Claims. (Cl. 40—132)

This invention relates to new and useful improvements in an electric advertising device, possessing a lighting effect similar to that of neon lamps.

5 The invention is intended to replace advertising signs constructed of neon lamps. This purpose is achieved by projecting the light of electric incandescent lamps on glass sheets mounted and prepared in a special manner, owing to which 10 arrangement the letters or pictures and figures painted on the said sheets will give the same effect as if neon tubes have been employed. By 15 means of the electric advertising device according to the invention a lighting effect making the letters or pictures and figures appear raised can 20 be obtained in a much simpler and less expensive manner than by means of the expensive neon tubes employed at present. A further advantage of the invention consists in the fact that in 25 daylight, the device may figure as an ordinary inscription, picture or figure, of any desired appearance whilst at night it will without any special arrangement, by simple lighting supply mains, create the perfect appearance of neon light.

Still further the invention proposes the construction of an electric advertising device as mentioned which is simple and durable and which may be manufactured and sold at a reasonable cost.

For further comprehension of the invention, and of the objects and advantages thereof, reference will be had to the following description and accompanying drawing, and to the appended 35 claims in which the various novel features of the invention are more particularly set forth.

In the accompanying drawing forming a material part of this disclosure:

Fig. 1 is a fragmentary front elevational view 40 of an electric advertising device constructed in accordance with this invention.

Fig. 2 is a transverse sectional vertical view taken on the line 2—2 of Fig. 1.

Fig. 3 is a vertical sectional view taken on the 45 line 3—3 of Fig. 2.

Fig. 4 is a front elevational view of the device, this view being similar to the view shown in Fig. 1, differing only in that the illustration of the rear pane of glass shown in dotted lines has 50 been omitted.

Fig. 5 is a vertical sectional view similar to Fig. 2 showing another embodiment of this invention.

Fig. 6 is another vertical sectional view similar to Fig. 2 but illustrating a still further embodiment 55 of this device.

Fig. 7 is a fragmentary horizontal sectional view taken on the line 7—7 of Fig. 6.

Fig. 8 is a fragmentary vertical sectional view taken on the line 8—8 of Fig. 7.

The electric advertising device in accordance 5 with this invention includes a container 10 having an open front side 10^a and illuminating means 11 mounted therein. This illuminating means comprises an incandescent lamp 11^a mounted on a suitable socket 12 connected in a suitable electric 10 circuit. Preferably a condenser 13 is associated with the incandescent lamp to diffuse the light from the lamp and throw it uniformly across the opening 10^a of the container.

An outer diaphanous sheet 14 of glass, Cellophane, Celluloid, or the like, is mounted across the open side 10^a, and has a symbol or symbols 15 painted or in any other manner printed on its outer face in material which is permeable to light. All other areas of the sheet 14 are covered with material 16 which is impermeable to light. At the area of the symbols 15 the impermeable material 16 is cut out so as to frame the material 15. Preferably the material 16 should be cut 20 slightly larger so that there is a very narrow frame 17 around the symbol or symbols 15. For purposes of illustration the symbols 15 have been illustrated in the low part of Fig. 4 so as to comprise letters 15^a. In the upper portion of Fig. 4 25 they comprise symbol configurations 15^b.

An inner diaphanous sheet 18 is mounted across the open side 10^a of the container 10 but spaced slightly inwards of the outer sheet 14 so that there is a space 19 between these sheets. 35 This inner sheet 18 has the same symbol or symbols painted or in any other manner imprinted thereon, and indicated by the reference numeral 15', distinguishing in the fact that this symbol or symbols are of smaller size than the symbols 15 so that light which may pass from within the container may fall upon the center part or parts 40 of the symbol 15. In Fig. 3 an elevational view has been shown of the sheet 18 wherein it may easily be noted that the symbols thereon are 45 identical to the symbols on the sheet 14 but of smaller size. In Fig. 1 these symbols have been shown superimposed.

The symbols 15' are arranged upon the inner face of the sheet 18 and are formed from material permeable to light. All other areas of the sheet 18 are covered with material 20 which is impermeable to light.

The impermeable materials 16 and 20 previously referred to preferably may be mirroring 55

material. This mirroring material may be silver or other materials used to produce mirrors.

The operation of the device is as follows:

The light from the incandescent lamp 11^a will be thrown uniformly across the inner face of the diaphanous sheet 18. At areas where the symbol or symbols 15' occur, the light may pass through and fall upon the areas 15, vividly illuminating center portions of these areas when the electric display device is viewed in the night time, from even only a short distance away and it will give the appearance of neon tubes. The vividly lighted area or areas will give the appearance of the tubes, and the surrounding areas upon the front sheet 14 which have the same symbols will give the effect of the haze usually found around neon tubes.

The symbol or symbols may be painted or imprinted in various desired colors. In the night time an effect will be given which simulates colored neon tubes. In the day time the symbols 15 upon the front sheet 14 will be clearly visible and if the lamp 11^a is lighted, vivid color of the symbols 15', situated behind it on the sheet 18 will also be seen. If desired, the lamp 11^a need not be used in the daytime.

In Fig. 5 a modified form of the invention has been illustrated which distinguishes from the prior form in several respects. According to this form of the invention the outer diaphanous sheet 14 is provided with a symbol or symbols 25 of material permeable to light arranged upon the rear face thereof. All other areas are covered with material 26 which is impermeable to light. This material 26 is also arranged upon the rear face of the sheet 14. The sheet 18 is constructed identically the same as in the prior form. The container 10 is illustrated with a door 10^b at its back adjacent the incandescent lamp 11^a, which may be opened for permitting replacement of the lamp when it is burned out.

In other respects this form of the invention is identical to the previous forms and similar parts may be recognized by the same reference numerals.

In Figs. 6 to 8 inclusive another form of the invention has been disclosed which distinguishes from the prior forms in the fact that the rear diaphanous sheet 18 is adjustably mounted. According to this form of the invention the sheet 18 is mounted in a frame 21. This frame is supported centrally at its sides by a trunnion which consists of trunnion elements 22. These trunnion elements are supported in an outer frame 23. This outer frame has several lugs 24 extending rearwards along the sides of the walls of the container 10. Clamp screws 28 are mounted upon the walls of the container and pass through elongated slots 29 formed in the lugs 24 for adjustably holding the frame 23 in various positions.

The frame 21 is adapted to pivot about its central trunnion. A means is provided for holding the frame in various pivoted positions. This means includes a slide 30 for each trunnion element slidably supported on bearing elements 31 mounted upon the walls of the container 10. Each slide 30 is formed with an opening 32 through which the trunnion element 22 passes. Each opening 32 is formed with a large end 32^a into which a collar 33 extends. This collar is mounted coaxially upon the trunnion element 32 and fixedly mounted on the side of the frame 21. Each opening 32 has a rear end 32^b which is reduced in size and has roughened sides which are

adapted to engage the collar 33 to hold the collar for turning. The outer end of the slide 30 has a laterally bent portion 34 serving as a handle by which the slide may be manipulated. In other respects this form of the invention is identical to the prior forms and the same parts may be recognized by the identical reference numerals.

The operation of the device is as follows:

The light from the incandescent lamp 11^a passes through the condensers 13, illuminating the front of the container 10. Some of the light passes through the permeable symbols 15' and 15 to produce the neon effect previously referred to. However the inner sheet 18 may be adjusted forwards or rearwards relative to the outer sheet 14 so as to focus the light which passes through the symbols 15' centrally upon the symbols 15^a. By moving the sheet 18 forwards or rearwards it is possible to increase or decrease the size of the light which falls on the symbols 15^a. Moreover when desired the slides 30 may be moved forwards to free the frame 21. Then the frame may be pivoted slightly clockwise or anti-clockwise as viewed in Fig. 6 so as to change the position of the light which passes through the symbols 15' and falls upon the symbols 15^a. In this way different effects of the neon effect may be obtained. The frame 21 may be locked in any inclined position by merely moving the slides 30 forwards again so that the reduced ends 32^b of the openings 33 grip the collars 33.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. An electric advertising device, comprising a container having an open side and illuminating means therein, an outer diaphanous sheet extending across said open side, symbols formed on the outer face of said outer sheet and of material permeable to light, an inner diaphanous sheet extending across said open side slightly inwards of said outer sheet forming a space between the adjacent faces of said sheets, like symbols formed on the inner face of said inner sheet also of material permeable to light and of a size slightly smaller than said symbols, and material impermeable to light formed on all other areas of the adjacent inner faces of said sheets.

2. An electric advertising device, comprising a container having an open side and illuminating means therein, an outer diaphanous sheet extending across said open side, symbols formed on the outer face of said outer sheet and of material permeable to light, an inner diaphanous sheet extending across said open side slightly inwards of said outer sheet forming a space between the adjacent faces of said sheets, like symbols formed on the inner face of said inner sheet also of material permeable to light and of a size slightly smaller than said symbols, and material impermeable to light formed on all other areas of the adjacent inner faces of said sheets, said impermeable material, comprising mirroring material for causing the light rays passing through the permeable symbols of said inner sheet to be reflected through the permeable symbols of said outer sheet.

3. An electric advertising device, comprising a container having an open side and illuminating means therein, an outer diaphanous sheet across said open side and having a symbol or symbols thereon in material permeable to light and all other areas being provided with material impermeable to light, and an inner diaphanous sheet across said open side spaced slightly inwards of said outer sheet and having the same symbol or symbols thereon in material permeable to light and smaller in size so that light from within said container may fall on the central part or parts of the symbol or symbols on the outer sheet, and all other areas of said inner sheet being provided with material impermeable to light, said impermeable material comprising mirroring material, said mirroring material being arranged upon the adjacent faces of said sheets, and said symbol or symbols being painted or imprinted on the remote faces of said sheets.

4. An electric advertising device, comprising a container having an open side and illuminating means therein, an outer diaphanous sheet across said open side and having a symbol or symbols thereon in material permeable to light and all other areas being provided with material impermeable to light, and an inner diaphanous sheet across said open side spaced slightly inwards of said outer sheet and having the same symbol or symbols thereon in material permeable to light and smaller in size so that light from within said container may fall on the central part or parts of the symbol or symbols on the outer sheet, all other areas of said inner sheet being provided with material impermeable to light, and means for adjustably holding said inner sheet so as to be movable forwards and rearwards.

5. An electric advertising device, comprising a container having an open side and illuminating

means therein, an outer diaphanous sheet across said open side and having a symbol or symbols thereon in material permeable to light and all other areas being provided with material impermeable to light, and an inner diaphanous sheet across said open side spaced slightly inwards of said outer sheet and having the same symbol or symbols thereon in material permeable to light and smaller in size so that light from within said container may fall on the central part or parts of the symbol or symbols on the outer sheet, all other areas of said inner sheet being provided with material impermeable to light, and means for adjustably holding said inner sheet so as to be movable forwards and rearwards, and be pivotally about the central horizontal axis.

6. An electric advertising device, comprising a container having an open side and illuminating means therein, an outer diaphanous sheet across said open side and having a symbol or symbols thereon in material permeable to light and all other areas being provided with material impermeable to light, and an inner diaphanous sheet across said open side spaced slightly inwards of said outer sheet and having the same symbol or symbols thereon in material permeable to light and smaller in size so that light from within said container may fall on the central part or parts of the symbol or symbols on the outer sheet, all other areas of said inner sheet being provided with material impermeable to light, and means for adjustably holding said inner sheet so as to be movable forwards and rearwards, and be pivotally about the central horizontal axis, and means for locking said inner sheet in various pivoted and forwards and rearwards adjusted positions.
